UNITED STATES PATENT OFFICE.

PHILO M. LOSSING, OF KALKASKA, MICHIGAN.

SURGICAL INSTRUMENT.

1,260,924.

Specification of Letters Patent. Patented Mar. 26, 1918.

Application filed August 6, 1915. Serial No. 44,011.

To all whom it may concern:

Be it known that I, PHILO M. LOSSING, a citizen of the United States, residing at Kalkaska, in the county of Kalkaska and 5 State of Michigan, have invented certain new and useful Improvements in Surgical Instruments; and I do hereby declare the following to be a full, clear, and exact description of the invention, such as will enable others skilled in the art to which it 10 appertains to make and use the same.

This invention relates to surgical instruments, and the primary object of the invention is to provide a device for withdrawing 15 obstructions from the esophagus or throat of an animal, which may have become lodged below the swallowing muscles.

Another object of this invention is to provide an instrument as specified, which includes a flexible hollow tube, and a flexible shaft for insertion through the tube, and further provides a spiral blade upon the end of the flexible shaft for insertion into a vegetable, which may be choking the animal, for withdrawing the same from the 20 throat of the animal without injuring the latter.

With the foregoing and other objects in view this invention consists in such novel 30 features of construction, combination and arrangement of parts as will be hereinafter more fully described, illustrated in the accompanying drawings and claimed.

In describing the invention in detail reference will be had to the accompanying drawing, wherein like characters designate 35 like and corresponding parts throughout the several views, and in which:—

Figure 1 is a view of the assembled instrument, showing parts in section,

Fig. 2 is a view of the tube, and

Fig. 3 is a side elevation of the shaft which is inserted in the tube.

Referring more particularly to the drawings, 45 1 designates the tube, which may be constructed of any suitable type of flexible material, so as to permit the same to bend for conformity to the curvature of the throat or esophagus of an animal. The tube 1 is hollow, and has its lower end rounded, so as not to injure the throat on entering the same.

The shaft, indicated at 5, which is inserted through the tube 1, is constructed of 50 flexible material, and preferably coiled flexible sheet metal, as indicated in Fig. 3

of the drawing. However, the shaft 5 may be constructed of any suitable type of flexible material, this feature depending upon the desires of the person manufacturing the 60 same.

The shaft 5 has a handle 6 secured to its upper end, and a screw or spiral blade 7 connected to its lower end. The spiral blade 7 terminates in a screw threaded 65 tapered inserting point 8, similar to the inserting point of a drill bit.

In the operation of the improved surgical instrument: when an animal chokes upon a vegetable, such as a potato, apple, beet or 70 the like, the tube 1 is inserted through the throat or esophagus of an animal until the inner end 2 engages the obstruction, indicated at 10 of Fig. 1 of the drawings, after which the shaft 5 is inserted through the 75 tube 1, and on the point 8, of the shaft engaging the obstruction 10, the same is rotated through the medium of the handle 6, which causes the spiral blade 7 to move into the obstruction and obtain a secure grip 80 upon the same, so that, when an outward pull is applied to the shaft 5 and the tube, the obstruction 10 will be removed from the esophagus of an animal without rupturing or materially injuring the same.

The device is particularly adaptable for use in cases where the animal has choked upon a vegetable which has been split or cut in two, as indicated in Fig. 1, at which time the ordinary manner of forcing the 90 obstruction downwardly through the throat of the animal would rupture the esophagus of the animal, and in all probability kill the animal.

Whereas, with the improved instrument 95 as described, the obstruction may be removed outwardly from the esophagus into the mouth of an animal, for mastication or entirely removed, as desired.

In reducing the invention to practice, certain minor features of construction, combination, and arrangement of parts may necessitate alteration, to which the patentee is entitled, provided such alterations are comprehended within the scope of what is 100 claimed.

What is claimed is:—

A surgical instrument comprising a hollow flexible cylindrical tube having its lower end flared and rounded and provided with a V-shaped notch opening outwardly of its lower end, a flexible and spirally wound member 110

in said tube, a spiral blade secured to the lower end of the member and having its free end tapered and screw threaded and a handle on the upper end of said member for 5 rotating the same to thread the threaded end of the blade into an obstruction and force the same into the V-shaped notch of the tube to prevent rotation of the obstruc-

tion in the throat of an animal while threading the spiral therein.

In testimony whereof I affix my signature in presence of two witnesses.

PHILO M. LOSSING.
